SIGHT CARD INDEX

Alphons Fürer, Solothurn, Switzerland

Application December 8, 1948, Serial No. 64,059
In Switzerland December 10, 1947

5 Claims. (Cl. 129—16.7)

1

The present invention relates to a sight card index with a pile of index cards lying behind each other.

In such sight card indexes it is desirable to have the separate cards in the pile easily separable from each other, so that the lettering becomes visible and the desired card can easily be found.

For this purpose, in the sight card index according to the present invention, at least one flap is fitted to the index cards above their longitudinal middle, so that the lower part of the flap can swivel away from the card.

One execution of the object of the invention is illustrated by way of example in the accompanying drawing, where

Fig. 1 shows a front view of an index card,
Fig. 2 a side view of the same and

Fig. 3 a side view of a number of cards arranged one behind the other.

The index card 1 shown in the drawing has at both sides, near the upper edge, a slit 2, which serves for taking a flap 3 consisting of transparent celluloid. The flaps 3 are provided at two opposite sides with a cut 4. The parts of the card 1 adjacent to the slit 2 lie in these cuts 4 of the flaps 3 so that the latter are held tippable in the slits 2. In order to be able to introduce the flaps into the slits 2, a cut 5 is made in the flap at right angles to the cuts 4, so that two wings are made in the flaps and can be pushed partly over each other. In this way the width of the flap, at the part leading into the slit and provided with the cut 5, can be temporarily diminished and the flap thus introduced into the slit 2 in the card 1.

As can be seen from Fig. 3, as soon as a slight pressure is exerted on the upper edge of the flaps 3 and no pressing is present on the cards normal to their sight surface and they are in a suitable upright position, the flaps 3 cause the cards to move out like a fan from each other, so that the lettering in their upper edges is visible and easy to read.

Instead of two flaps only one can be arranged, for instance in the middle of the card.

Instead of the transparent celluloid flaps, flaps of some other material can be used, for instance metal flaps, which in order to save space can be made thinner than the celluloid flaps while still having approximately the same bending strength.

What I claim is:

1. An index card unit comprising a pack of cards lying one behind another, each of a plu-

2

rality of said cards having a slit that is closed at both ends and is spaced from the edges of the card, being approximately parallel to one edge of the card, a flap of resilient material having a width greater than the length of said slit, said flap having notches opposite one another in its side edges at approximately the middle of the flap in a lengthwise direction to provide a portion of reduced width which is received in and extends through the slit of the card and to provide shoulders which engage the card at opposite sides of a line forming an extension of said slit, the engagement of the opposite edges of the slit with opposite sides of the flap and the engagement of said shoulders with the card tending resiliently to tilt the flap at an angle to the plane of said card to separate adjacent cards slightly when unconfined, said flap being freely swingable about said slit as a pivot further to separate adjacent cards angularly from one another while remaining flat, said cards being wholly unconnected and free from one another and freely liftable completely out of the pack by said flaps.

2. An index card unit comprising a pack of cards lying one behind another, each of a plurality of said cards having a slit that is closed at both ends and is spaced from the edges of the card, being approximately parallel to one edge of the card, a flap of resilient transparent material having a width greater than the length of said slit, said flap having notches opposite one another in its side edges at approximately the middle of the flap in a lengthwise direction to provide a portion of reduced width which is received in and extends through the slit in the card and to provide shoulders which engage the card at opposite sides of a line forming an extension of said slit, said flap having a slit extending up from the lower edge of the flap and intersecting a line connecting said notches, the engagement of the opposite edges of the slit in the card with opposite sides of the flap and the engagement of said shoulders with the card tending resiliently to tilt the flap to a position at an angle to the plane of said card, said flap being freely swingable about said slit as a pivot to separate adjacent cards angularly from one another while remaining flat, said cards being wholly unconnected and free from one another and freely liftable completely out of the pack by said flaps.

3. A card index comprising a plurality of separate and unconnected cards, each of said cards having a slit that is closed at both ends and is spaced from and approximately parallel to the

upper edge of the card, a flap of resilient transparent material having a width greater than the length of the slit, said flap having notches opposite one another in its side edges to provide a portion of reduced width which is received in and extends through said slit and to provide shoulders at the opposite sides of said notches which engage opposite faces of the card on opposite sides of a line forming an extension of said slit, the engagement of the opposite edges of said slit with opposite faces of said flap and the engagement of said shoulders with the card tending resiliently to tilt the flap to a position at an angle to the plane of said card to spread adjacent cards slightly apart, said flap projecting above the upper edge of the card and being freely swingable about said slit as a pivot further to separate adjacent cards angularly from one another while remaining flat, said cards being wholly unconnected and free from one another and freely liftable completely out of the pack by said flaps.

4. A card index comprising a pack of cards lying one behind another, each of a plurality of said cards having a slit below and approximately parallel to the upper edge of the card and above its longitudinal center line, and a flap associated with each of said slotted cards, said flap being formed of resilient material and having a width greater than the length of the slit with notches in opposite side edges in the mid-portion of the flap to form a portion of reduced width which is received in and extends through the slit to provide a hinge connection between the flap and said card, the top portion of the flap projecting above the top of the card and the lower portion of the flap projecting below said slit on the opposite side of the card from the top portion, pivotal movement of the flap about said slit as an axis causing the lower portion of the flap to swing out away from the card and separate adjacent cards angularly from one another while remaining substantially flat, said cards being wholly unconnected and free from one another and being freely liftable completely out of the pack without lifting adjacent cards.

5. A card index comprising a pack of cards of uniform height lying one behind another in an approximately upright position, each of successive cards having a slit below and approximately parallel to the upper edge of the card and in the upper quarter of the card, and a flap associated with each of said slotted cards, said flap being formed of resilient material and having a width greater than the length of said slit with notches in opposite side edges in the mid-portion of the flap to form a portion of reduced width which is received in and extends through said slit to provide a hinge connection between the flaps and said card, the top portion of the flap projecting up above the upper edge of the card and the lower portion of the flap projecting below said slit and lying wholly on the opposite side of the card from the top portion, said flap being freely swingable about said slit as an axis to engage adjacent cards and separate them angularly from one another while remaining substantially flat, said cards being wholly unconnected and free from one another and being individually liftable completely out of the pack.
